Primary Examiner — Karen S Acker(74) Attorney, Agent, or Firm — Cantor Colburn LLP(57) CLAIM

The ornamental design for a label with pattern, as shown and described.

DESCRIPTION

FIG. 1 is a top plan view of a label with pattern showing my new design; and,

FIG. 2 is an enlarged detail view of the area circumscribed on FIG. 1.

The broken line surrounding FIG. 1 represents the boundaries of the label with pattern and forms no part thereof. The broken line within FIG. 1 and surrounding FIG. 2 represent the boundaries of the detail and form no part thereof. The sides and the bottom surfaces of the label with pattern form no part of the claimed design.
